SUBSTRUCTURE FOR OIL WELL DERRICKS

Samuel B. Settle and Herbert A. Johnson, Parkersburg, W. Va., assignors to The Parkersburg Rig & Reel Company, Parkersburg, W. Va., a corporation of West Virginia

Application September 12, 1935, Serial No. 40,332

15 Claims. (Cl. 189—21)

This invention relates to substructures for oil well derricks.

In the erection of oil well derricks, it formerly was the practice to employ various types of supporting structures for the derricks. For example, derricks were mounted on poured concrete piling, wood piling and cribbing, and other heavy timbered supports, depending upon the location of the derrick.

More recently it has become the practice to provide steel supporting substructures for derricks, such substructures having been originally employed in wet and swampy locations and their use having extended generally for the supporting of derricks in all localities because of their inherent advantages. For example, a steel substructure can be fabricated from structural elements in such a manner as to form particularly efficient supporting means for the derrick, with the derrick supported a substantial distance above the surrounding ground, thus making it unnecessary to excavate a cellar to provide accessibility to bolts, pipe fittings, blow out preventers and other equipment which is installed under the working floor of the derrick.

An important object of the present invention is to provide substantial improvements in fabricated derrick substructures to provide numerous additional advantageous features.

More specifically, an important object of the present invention is to provide a novel substructure wherein the weight of the parts is reduced while providing additional strength for supporting the derrick.

A further object is to provide a substructure which includes a minimum number of parts and which provides interchangeability of parts, thus facilitating the manufacture, erection and dismantling of the structure.

A further object is to provide a substructure having a high degree of portability, since it may be transported in knocked down condition and easily erected by the usual derrick crews.

A further object is to provide a substructure which operates as a permanent support for a derrick and which includes supporting means for use in mechanisms used in the drilling of a well, such as the engine, draw works, etc., the supporting means being readily capable of being dismantled for use with other substructures.

A further object is to provide a substructure which substantially reduces fire hazards, thus protecting the derrick and mechanism associated therewith from injury.

A further object is to provide a structure of

the character referred to which is capable of being completely salvaged, as distinguished from the earlier structures wherein there could be substantially no salvaging of the concrete and/or timber supporting means employed.

A further object is to provide a derrick substructure having novel corner columns which operate more efficiently for carrying loads and strains and stresses of various types to which a supporting structure of this character is subjected.

A further object is to provide a substructure of the character referred to wherein the novel arrangement of the corner columns with relation to the legs of the derrick is such that the vertical plane of the neutral axis of each derrick leg coincides with the vertical plane of the web of the structural elements used for each corner column.

Other objects and advantages of the invention will become apparent during the course of the following description.

In the drawings we have shown one embodiment of the invention. In this showing:

Figure 1 is a plan view of the substructure, 25

Figure 2 is a side elevation of the same, showing a portion of two of the derrick legs,

Figure 3 is an enlarged side elevation of one corner portion of the substructure, parts being broken away,

Figure 4 is a section on line 4—4 of Figure 3, and,

Figure 5 is a section on line 5—5 of Figure 3.

Referring to Figures 1 and 2, the numeral 10 designates the substructure as a whole and, as will become apparent, this substructure is adapted to support the usual derrick both during the drilling of a well and during production therefrom. It also will become apparent that the same derrick may be employed during drilling 40 and production, or, after a well has been drilled in, the derrick may be removed and replaced by a production derrick without disturbing the substructure in any manner. The substructure is substantially square in plan as indicated in Figure 1 and comprises four corner columns 11 which form the principal supporting means. Each of the columns 11 is of the H-beam type including bases 12 and 13 connected by the usual web 14. The corner columns are preferably vertically arranged as shown in Figures 2 and 3 and each has its web arranged in the same vertical plane as the diagonally opposite column.

Girders 15 are employed for connecting the upper ends of the corner columns. At each of

the corner columns a connecting plate 16 is employed for connecting the columns to the adjacent ends of the two adjacent girders 15. Each plate 16 is bent to form end portions 17 and 18, 5 and the end portion 17 of each connecting plate is bolted as at 19 to the adjacent end of the adjacent girder 15. The other ends 18 of the connecting plates are riveted as at 19' to the bases 13 of the respective corner columns, and 10 each plate portion 18 is also welded as at 20 to its associated column base 13. In manufacturing the apparatus at the factory the connecting plates may be riveted as at 19' to the columns and then welded in position, thus making a permanent joint between these elements. Corner 15 portions of the girders 15 may be angularly braced by channel iron or similar braces 20', bolted beneath the girders 15 as indicated in Figure 2.

20 A cap plate 21 is arranged over the top of each column, the latter elements being squared on their upper ends to permit the cap plates to seat thereon. These cap plates are welded to the upper ends of the columns as at 22 and a corner plate 23 is arranged in the angle between each cap plate 21 and the outer face of the adjacent base 13 of the adjacent column as shown in Figure 3, and is welded to both of these elements. As shown in Figure 4, the outer corner 30 of each cap plate overhangs the outer limit of the adjacent column and the angle supports 23 adequately brace the overhanging corners of the cap plates 21.

Lower girders 24 are arranged between the 35 lower ends of the adjacent pairs of corner columns and are bolted as at 25 to connecting plates (not shown) which are identical with the plates 16 previously described, except as to their width, the width of the lower connecting plates 40 corresponding to the width of the girders 24. The lower girders 24 extend throughout the length only of the sides of the substructure wherein no interference occurs with any apparatus used in connection with the derrick. For example, Figure 2 of the drawings illustrates an 45 elevation of the ladder side of the substructure, a space 26 being left for mud box clearance between angular braces 27 connected at their upper ends to the adjacent girder 15 and at their 50 lower ends to the inner ends of the girder sections 24. All sides of the substructure are suitably braced as indicated generally by the numeral 28, the particular type of bracing being of no particular importance in connection with the 55 present invention.

The substructure is adapted to support the usual derrick, the legs of which are indicated in the drawings by the numeral 29. In accordance with the usual practice, the legs of the derrick 60 are made of angle section, as shown in Figure 4, and the lower end of each derrick leg is provided with a base plate 30 welded thereto and bolted to the cap plate 21 as at 31. Attention is invited to the fact that the bolts 31 occupy 65 the positions set as standard in the accepted specifications in the art to which the present invention relates, and accordingly the conventional positions of these bolts need not be changed in employing the present invention.

70 The derrick tapers to decrease in size toward its upper end, as is well known, and the diagonally opposite derrick legs incline toward each other in a common plane. This common plane, in the present apparatus is made to coincide 75 with the common plane of the diagonally oppo-

site column webs 14. Referring to Figure 4 the neutral axis of one of the derrick legs 29 is indicated by the numeral 32, and it will be noted that this axis substantially coincides with the neutral axis of the associated column 11. In 5 other words, the load carried by each derrick leg centers with respect to the neutral axis 32 of such leg and this axis lies over the associated corner column web 14 and directly in the plane thereof. Moreover, the loads carried 10 by diagonally opposite derrick legs are confined to a plane which is coincident with the common vertical plane of the web portions of the associated diagonally opposite corner columns 11.

The substructure is supported in any suitable 15 manner. Each column 11 is provided at its lower end with a base plate 33 welded thereto and a corner brace 34 similar to the plate 23 may be employed in connection with each base plate 33, each plate 34 being preferably welded 20 to its associated base plate 33 and the corner column base 13. The base plates 33 are bolted or otherwise secured to the particular type of foundation employed. Such foundations, for example, may comprise wood piling, the combination of a wood mat and conventional steel grillage, etc., the particular foundation means for the substructure being of no importance per se, so far as the present invention is concerned. As previously stated, the substructure may be 30 left standing undisturbed after a well is drilled in in order to support the production derrick, and the substructure is adapted to carry supporting means for the engine, rotary draw works, etc. For example, such supporting means may be arranged as shown in Figure 1 and indicated as 35 a whole by the numeral 35. Such supporting means may include various horizontal structural members 36, 37, 38 and 39, depending upon the kind and disposition of the apparatus to 40 be supported thereby, and may further include angular braces 40. All of the elements comprising the supporting means 35 are preferably bolted to the elements of the substructure so as to be removed therefrom after the drilling 45 operation is completed.

The operation of the apparatus is as follows:

A suitable foundation is laid down for the substructure, such foundation, of course, being limited in height as distinguished from the use 50 of relatively high poured concrete supporting posts, cribbing, etc. as formerly employed in particularly wet or marshy land. The base plates 33 are then secured in proper position on the foundation with the columns 11 occupying 55 their desired positions in the substructure. The entire substructure is constructed at the site, except as to such elements as the cap plates 21, base plates 33 and tie plates 16 which are welded in position at the factory. After the complete 60 erection of the permanent substructure elements including the columns 11, girders 15, etc., the temporary supporting structure 35 is erected to support the apparatus employed in the drilling of the well, such as the engine, rotary draw 65 works, etc. The derrick is erected over the substructure exactly in accordance with present practice, it having been pointed out that the securing bolts 31 for the derrick leg base plates 30 occupy the same position as laid down in the 70 specifications of the industry.

The various apparatus employed in connection with the drilling of the well is then installed on the supporting means provided for this purpose, such as the supporting structure 35, and 75

the drilling of the well is carried out in the usual manner. After the drilling of the well has been completed, the elements comprising the supporting structure 35 may be dismantled and transported to a different site to be erected in connection with another substructure frame. Accordingly it will be apparent that it is unnecessary to provide a supporting structure 35 for each main substructure, and the cost of successive installations is thus materially reduced.

In previous substructures fabricated from structural steel it has been the practice to employ largely angle and channel members for all of the parts of the substructure including the supporting legs or columns. It has been found that a much lighter and less expensive structure can be provided by the arrangement of the parts disclosed, particularly with relation to the use and arrangement of the form of corner columns described. It will be noted that each corner column is provided with a vertical supporting portion lying in the vertical plane of the neutral axis of the derrick leg supported thereby. It is also particularly noted that the webs of diagonally opposite columns are arranged in a common vertical plane which is also the common vertical plane of the neutral axes of the two corresponding derrick legs. Likewise it will be apparent that the webs of the corner columns substantially bisect the angles between the sides of the substructure. It also will be noted that the flanges of the corner columns are arranged perpendicular to a line drawn diagonally from corner to corner of the substructure. It has been found that the arrangement of parts referred to greatly strengthens the substructure against the strains and loads to which it is subjected such as the dead weight of the derrick, drilling impacts, vibrations and wind load, at the same time permitting the use of a lighter substructure. Thus, a cheaper and more efficient substructure is provided which may be more readily and quickly assembled due to the lightness of the parts and the minimum weight thereof.

The construction disclosed embodies numerous other advantageous features. For example, it eliminates the fire hazard present in a derrick structure wherein the derrick is supported on timbering of various kinds. With such latter constructions it has been found in practice that the burning of the heavy timbers creates an intense heat such as to cause the complete collapse of a derrick and irreparable damage to the rotary machinery. In the present case, of course, a wood-derrick floor will be laid over the substructure and such flooring may burn but will not cause the intense heat present in the burning of heavy supporting timbers, and in the case of the burning of the derrick floor the steel substructure will remain intact and will preserve the rotary equipment and steel derrick unimpaired.

Moreover, the substructure provides a natural cellar beneath the derrick floor, thus facilitating accessibility to equipment which is ordinarily installed beneath the working floor of the derrick. In this connection, it will be noted that it was the former practice to support derricks a substantial distance above the ground only in wet or marshy land, but the structure of the present apparatus makes its use highly advantageous in all installations. The structure is also capable of complete salvaging, which ob-

viously is not true of previous types of derrick supports.

It is to be understood that the form of the invention herewith shown and described is to be taken as a preferred example of the same and that various changes in the shape, size and arrangement of parts may be resorted to without departing from the spirit of the invention or the scope of the subjoined claims.

We claim:

1. A substructure for derricks comprising a polygonal frame including a corner column at each corner thereof, each column having a flat portion arranged in a vertical plane substantially bi-secting the angle of the associated corner of said frame, and means for rigidly supporting the lower end of a derrick leg over and with respect to the upper end of each corner column.

2. A substructure for derricks comprising a polygonal frame including a corner column at each corner thereof, said columns being arranged in diagonally opposite pairs, the columns of each diagonally opposite pair having a flat portion arranged in a common vertical plane, and means for rigidly supporting the lower end of a derrick leg over and with respect to the upper end of each corner column.

3. A substructure for derricks comprising a polygonal frame including a corner column at each corner thereof, each column having a flat portion arranged in a vertical plane substantially bi-secting the angle of the associated corner of said frame, girders arranged between each adjacent pair of corner columns at the upper ends thereof, tie plates connecting each end of each girder to the adjacent corner column, and means for rigidly supporting the lower end of a derrick leg over and with respect to the upper end of each corner column.

4. A substructure for derricks comprising a polygonal frame including a corner column at each corner thereof, said columns being arranged in diagonally opposite pairs, each column of each pair having a flat portion arranged in a common vertical plane, girders extending between each adjacent pair of corner columns at the upper ends thereof, tie plates connecting each end of each girder to the adjacent corner column, and means for rigidly supporting the lower end of a derrick leg over and with respect to the upper end of each corner column.

5. A substructure for derricks comprising a polygonal frame including a corner column at each corner thereof, each column having a flat portion arranged in a vertical plane substantially bi-secting the angle of the associated corner of said frame, and a cap plate fitting against and secured to the upper end of each corner column and having bolt openings for rigidly securing the lower end of a derrick leg with respect thereto.

6. A substructure for derricks comprising a polygonal frame including a corner column at each corner thereof, said columns being arranged in diagonally opposite pairs, the columns of each diagonally opposite pair having a flat portion arranged in a common vertical plane, and a cap plate fitting against and secured to the upper end of each corner column and having bolt openings for rigidly securing the lower end of a derrick leg with respect thereto.

7. A substructure for derricks comprising a polygonal frame including a corner column at each corner thereof, each column having a flat

portion arranged in a vertical plane substantially bi-secting the angle of the associated corner of said frame, supporting means detachably carried by said frame wholly independently of said corner columns, and means for rigidly supporting the lower end of a derrick leg with respect to the upper end of each corner column.

8. A substructure for derricks comprising a polygonal frame including a corner column at each corner thereof, each column having a flat portion arranged in a vertical plane substantially bi-secting the angle of the associated corner of said frame, girders arranged between each adjacent pair of corner columns at the upper ends thereof, tie plates connecting each end of each girder to the adjacent corner column, supporting means detachably carried by said girders, and means for rigidly supporting the lower end of a derrick leg with respect to the upper end of each corner column.

9. The combination with a derrick having downwardly diverging legs, of a substructure for supporting the derrick comprising a frame having a plurality of vertical corner columns corresponding in arrangement to the lower ends of the derrick legs, each column having a flat portion arranged in the vertical plane of the neutral axis of one of the derrick legs, and means for rigidly supporting the lower end of each derrick leg with respect to its associated corner column.

10. The combination with a derrick having downwardly diverging supporting legs arranged in diagonally opposite pairs, of a substructure for supporting the derrick comprising a polygonal frame having diagonally opposite pairs of corner columns vertically arranged and corresponding in position to the lower ends of the legs of the derrick and arranged therebeneath, each corner column of each pair having a web portion lying in a common plane and in the vertical plane of the neutral axes of a diagonally opposite pair of derrick legs, and means for rigidly supporting the lower ends of the derrick legs with respect to the upper ends of the corresponding corner columns.

11. The combination with a derrick having downwardly diverging supporting legs arranged in diagonally opposite pairs, of a substructure for supporting the derrick comprising a polygonal frame including diagonally opposite pairs of corner columns vertically arranged and corresponding in position to the lower ends of the derrick legs, each corner column being of H-beam section with the flanges of each beam section arranged perpendicular to the web thereof, each web of each pair of diagonally opposite columns lying in a common plane and in the common plane of the neutral axes of a pair of diagonally opposite derrick legs, and means for rigidly supporting the lower ends of the derrick legs with respect to the upper ends of the corresponding columns.

12. The combination with a derrick having downwardly diverging supporting legs arranged in diagonally opposite pairs, of a substructure for supporting the derrick comprising a polygonal frame having diagonally opposite pairs of corner columns vertically arranged and corresponding in position to the lower ends of the legs of the derrick and arranged therebeneath, each corner column of each pair having a web

portion lying in a common plane and in the vertical plane of the neutral axes of a diagonally opposite pair of derrick legs, a cap plate rigidly secured to the upper end of each corner column, a base plate rigidly secured to the lower end of each derrick leg, and means for securing each base plate to one of said cap plates.

13. The combination with a derrick having downwardly diverging supporting legs arranged in diagonally opposite pairs, of a substructure for supporting the derrick comprising a polygonal frame including diagonally opposite pairs of corner columns vertically arranged and corresponding in position to the lower ends of the derrick legs, each corner column being of H-beam section with the flanges of each beam section arranged perpendicular to the web thereof, each web of each pair of diagonally opposite columns lying in a common plane and in the common plane of the neutral axes of a pair of diagonally opposite derrick legs, a cap plate rigidly secured to the upper end of each corner column, a base plate rigidly secured to the lower end of each derrick leg, and means for securing each base plate to one of said cap plates.

14. The combination with a derrick having downwardly diverging supporting legs arranged in diagonally opposite pairs, of a substructure for supporting the derrick comprising a polygonal frame having diagonally opposite pairs of corner columns vertically arranged and corresponding in position to the lower ends of the legs of the derrick and arranged therebeneath, each corner column of each pair having a web portion lying in a common plane and in the vertical plane of the neutral axes of a diagonally opposite pair of derrick legs, girders arranged between each adjacent pair of corner columns at the upper ends thereof, tie plates connecting each end of each girder to a flange of the adjacent corner column, a cap plate rigidly secured to the upper end of each corner column, a base plate rigidly secured to the lower end of each derrick leg, and means for securing each base plate to one of said cap plates.

15. The combination with a derrick having downwardly diverging supporting legs arranged in diagonally opposite pairs, of a substructure for supporting the derrick comprising a polygonal frame including diagonally opposite pairs of corner columns vertically arranged and corresponding in position to the lower ends of the derrick legs, each corner column being of H-beam section with the flanges of each beam section arranged perpendicular to the web thereof, each web of each pair of diagonally opposite columns lying in a common plane and in the common plane of the neutral axes of a pair of diagonally opposite derrick legs, girders arranged between each adjacent pair of corner columns at the upper ends thereof, tie plates connecting each end of each girder to a flange of the adjacent corner column, a cap plate rigidly secured to the upper end of each corner column, a base plate rigidly secured to the lower end of each derrick leg, and means for securing each base plate to one of said cap plates.

SAMUEL B. SETTLE.
HERBERT A. JOHNSON.
